DESIGN FOR A PLAYING CARD BOX AND DISPENSER

David M. Holstein, Syracuse, N. Y., assignor to Alexander E. Holstein, Philip M. Holstein, David
M. Holstein and Moses Winkelstein, a copartnership doing business as Syracuse Ornamental Co., Syracuse, N. Y.

Application November 22, 1941, Serial No. 104,262

Term of patent 7 years

To all whom it may concern:

Be it known that I, David M. Holstein, a citizen of the United States, residing at Syracuse, county of Onondaga, and State of New York, have invented a new, original, and ornamental Design for Playing Card Box and Dispenser, of which the following is a specification, reference being had to the accompanying drawing, forming a part thereof, wherein:

Fig. 1 is a top perspective view of a playing

card box and dispenser showing my new design;
and

Fig. 2 is a perspective view thereof showing the box in partially open position.

The side and end of the box not shown are substantial duplicates of those shown.

I claim:

The ornamental design for playing card box
and dispenser, as shown and described.

DAVID M. HOLSTEIN.
